UNITED STATES PATENT OFFICE.

ERNEST W. ANDERSEN, OF SAN FRANCISCO, CALIFORNIA.

DESIGN FOR AN ASPARAGUS-DISH.

42,682.

Specification for Design.

Patented July 2, 1912.

Application filed November 25, 1911. Serial No. 662,520. Term of patent 7 years.

To all whom it may concern:

Be it known that I, ERNEST W. ANDERSEN, a citizen of the United States, residing at San Francisco, in the county of San Francisco and State of California, have invented a new, original, and ornamental Design for Asparagus-Dishes, of which the following is a specification, reference being had to the accompanying drawing, forming a part thereof.

Figure 1 is a plan view of an asparagus dish showing my design. Fig. 2 is a side elevation of the same.

I claim:

The ornamental design for an asparagus dish, as shown.

ERNEST W. ANDERSEN. [L.S.]

Witnesses:

J. HEITMAN CHRISTENSEN,
W. R. LAWTON.
